[57] CLAIM

The ornamental design for a dual container package, as shown and described.

DESCRIPTION

FIG. 1 is a perspective view of a dual container package embodying my new design;

FIG. 2 is a top plan view;

FIG. 3 is an end elevational view;

FIG. 4 is a side elevational view; and

FIG. 5 is a bottom plan view.

The broken lines showing packaged items are for the purpose of illustrating environmental use only.

FIG. 1

FIG. 3

FIG. 2

FIG. 4

FIG. 5
